FASTENING ELEMENTS FOR SLIDING FASTENERS OF THE INVISIBLE TYPE

Alberto Camprubi Planas, Sabadell, Spain

Application April 22, 1952, Serial No. 283,549

Claims priority, application Spain February 23, 1952

1 Claim. (Cl. 24—205.13)

The present invention relates to improvements in fastening elements for sliding fasteners of the invisible type.

Fastening elements for sliding fasteners of the kind referred to are well known wherein the said elements, either symmetric or not, have to be arranged for working at the one side and at the opposite, thus there being provided right hand and left hand elements. These are symmetric or not in itself, but the ones with respect to the others in the opposite side are not alike but symmetric in the arrangement of the linking tooth.

Such an arrangement means a duplicity of machinery in the manufacture and stringing of said elements in order to form the sliding fasteners, as it is obvious that there has to be some variations in order to obtain the elements for both the sides and for the stringing thereof, due to which fact, setting up an industry of that kind is expensive in comparison with that for the manufacture of single elements for common sliding fasteners.

It has been found that providing the linking tooth not only on one of the element arms but in the contrary too, there will result, on each fastening element, two linking teeth protruding from one and the same face thereof, the suitable recesses formed in the operation for the manufacture of the said teeth being left in the opposite face.

With the fastening elements arranged in such a manner, the same are likewise applicable to both the sides of the fastener, thus doing away with the necessity of elements for the right hand side and elements for the left hand side, and both the kinds of elements are reduced to a single one that definitely answers the purpose of both the sides of the fastener.

This feature which at first view may appear to be only important to the fastener is, however, transcendent for the manufacture thereof as the number of machines involved in its fabrication and to form the invisible sliding fastener is reduced to the half. At present, there are machines of two different kinds for the manufacture of the fastener elements, one for the elements of the right hand side and another for the elements of the left hand side, and stringing of the elements has to be performed onto different tapes, one for each side of the fastener, etc.

The present invention makes it possible that the manufacture of the standardized elements can be performed by a single machine and the utilization of a single tape, and a single machine for the stringing thereof onto a tape.

The elements fixed onto a tape will, thus, be identically arranged, and as a characteristic feature to define which side of the fastener they have to be applied to, it is only necessary to iron the tape towards the right or left side of the elements in order to thereby obtain, of course, the invisible sliding fastener.

In order that the nature and scope of the present invention may be clearly understood, reference is made to the following detailed description, taken in considera-

2

tion with the accompanying sheet of drawings showing a single embodiment only by way of example.

In the drawings:

Fig. 1 shows diverse embodiments of fastening elements;

Fig. 2 is a view of the element taken from the lower edge thereof;

Fig. 3 shows a fastening element fixed onto a tape, and in dotted lines the tape bent to the other side, and

Fig. 4 is a transversal section of a plurality of elements forming the sliding fastener, in linked arrangement.

With reference to Fig. 1, as parts of the element are indicated the body 1, the arms 2 and 3, the section 4 having the smallest resistance and the development arch 5 which once the element is fixed to the tape gives place to a straight edge and, finally, the linking teeth 6 arranged on each arm, thus resulting in two linking teeth on each fastening element.

The element so arranged is strung onto the tape 10 by means of a symmetrical clamping action, thus giving place to clamping of the element against the thickened edge 8 as is shown in Fig. 3.

The element is provided in the face opposite to that which has the teeth with recesses 7 obtained in the formation of the same, by means of which perfect linking is obtained either on one side or on the opposite with respect to the above referred teeth 6.

The tape with the fastener elements secured thereon may be ironed or pressed towards one side (full lines in Fig. 3) or towards the opposite side (dotted lines in Fig. 3).

The linking of the fastener is clearly appreciated in Fig. 4, wherein each tooth 6 engages with the recess 7 of the opposite element, the similar elements 1 thus remaining forming the invisible sliding fastener, which as may be appreciated is deprived of a definite flank, there not being elements for the right hand side and different elements for the left hand side, but a single type of element with the corresponding simplification which this fact allows to in the industry of the referred invisible sliding fasteners.

The invention may be carried into practice in other embodiments differing in its detail from those given only as a way of illustrative example for the preceding description and to which the claimed protection will likewise extend. It may, thus, be fabricated in any shape and size, utilizing in the manufacture thereof the materials most suitable to each case of embodiment, combined in the most convenient way to reach the proposed end as all this will be comprehended within the spirit of the present claim.

Once described and ascertained the nature of my said invention and in what manner the same is to be performed, I declare that what I claim is:

Improvements in separable fasteners of the invisible type including a flat tape having a bead along one edge and a set of fastening elements, each element comprising a body portion of elongated form provided with an opening intermediate the ends thereof with the opening extending from one edge to substantially the opposite edge to define a longitudinally weakened edge, the said opening also providing a similar arm at each end of the body portion on opposite sides of the opening with such arms extending outwardly at an angle to the longitudinally weakened edge, a linking tooth on each arm extending parallel to the sides of the arm, with each tooth protruding from the same face of the respective arms, each arm having on its opposite face, a recess corresponding to said tooth and extending parallel to the sides of the arm, the said teeth and recesses being substantially in line with the opening in the body portion, the upper end of each arm being inclined downwardly to the opening so that

such ends of the arm form a trough-like depression, with the end of each arm remote from the opening being rounded and the bead on the tape being insertable into the opening so that when pressure is applied to the ends of the body portion, the respective arms are moved toward each other by virtue of the longitudinally weakened edge of the body portion to anchor the tape bead in the opening with one edge of the said tape overlying at least one arm of the body portion and to displace the teeth and recesses to a position perpendicular to the longitudinally weakened edge of the body portion.
